Primary Examiner — Cynthia Ramirez*Assistant Examiner* — Llorellys Martinez-Rivera(57) **CLAIM**

The ornamental design for a bracelet, as shown and described.

DESCRIPTION

FIG. 1 is a front perspective view of a bracelet showing my new design;

FIG. 2 is a rear perspective view thereof;

FIG. 3 is a front view thereof;

FIG. 4 is a rear view thereof;

FIG. 5 is a side view thereof; and,

FIG. 6 is a bottom view thereof.

The broken line portions shown in FIGS. 1 through 5 illustrate environmental subject matter only and form no part of the claimed design.
